UNITED STATES PATENT OFFICE.

CHARLES A. STURTEVANT, OF PLAINFIELD, NEW JERSEY.

TURBINE-ENGINE.

No. 930,503.

Specification of Letters Patent.

Patented Aug. 10, 1909.

Application filed December 28, 1907. Serial No. 408,376.

To all whom it may concern:

Be it known that I, CHARLES A. STURTEVANT, a citizen of the United States, and resident of Plainfield, in the county of Union and State of New Jersey, have invented a new and useful Improvement in Turbine-Engines, of which the following is a specification.

This invention relates to a turbine engine and has as its object to produce an engine of this character which is very simple, durable and compact in construction and which yields the maximum amount of power in proportion to the amount of pressure medium which is expended.

The engine shown in the drawings is more particularly intended to be driven by steam but the same may be organized to utilize another pressure medium such for instance as exploding gas.

In the accompanying drawings consisting of 3 sheets: Figure 1 is a vertical axial section of my improved turbine engine in line 1—1, Fig. 2. Fig. 2 is a vertical diametrical section thereof taken in line 2—2, Fig. 1. Fig. 3 is a fragmentary sectional view, on an enlarged scale, of one of the outlet or delivery nozzles for the pressure medium. Fig. 4 is a vertical longitudinal section in line 4—4, Fig. 2. Fig. 5 is a vertical cross section in line 5—5, Fig. 4. Figs. 6 and 7 are detached face views of the impulse wheel and one part of the reaction wheel of the engine. Fig. 8 is a fragmentary vertical longitudinal section 35 showing a modified construction of a turbine engine embodying my invention. Fig. 9 is a transverse section of the same.

Similar letters of reference indicate corresponding parts throughout the several views. The casing or housing of my improved turbine engine may be variously constructed but as shown in the drawings the same preferably consists of two upright disks or walls A, A¹ arranged one in front of the other and having their inner portions comparatively far apart while their outer portions are arranged closer together, and a ring B secured between the peripheral portions of the disks by bolts b or otherwise. This casing is supported in an upright position preferably by standards or legs c secured to the lower parts thereof. D represents a stationary arbor supported in a hub w on the front disks or wall of the casing and in line with the axes of said disks. This arbor is made hollow so as to form a longitudinal supply conduit d therein which

is connected at its outer end by any suitable means with the source from which the pressure medium is supplied. Inasmuch as the engine in the drawing is more particularly designed to be driven by steam the following description will refer more particularly to this pressure medium as the source of power. The inner end of the arbor is arranged within the central part of the inclosing casing and is provided with a laterally opening supply port e extending from the supply conduit to the periphery of the arbor.

Opposite the arbor and axially in line therewith is a main shaft having a front or inner hollow section F which turns on the opposing inner end of the arbor and an outer or rear solid section F¹ which projects through the rear wall of the casing. The hollow portion of this shaft is provided with a circular row of openings or ports f which are adapted to register successively with the supply port of the arbor upon rotating said shaft upon the arbor. Within the casing is arranged a reaction wheel which comprises front and rear disks H, H¹, a hub I connecting the inner parts of said disks and mounted upon the hollow part of the shaft F, F¹, a rim or peripheral flange J connecting the outer parts of said disks and a plurality of radial ribs or partitions K connecting said disks and extending from the rim of the hub. The disks, hub, rim and partitions of the reaction wheel thus form a circular row of steam chambers L within the reaction wheel. Six of such chambers are shown in the drawings although the number may be varied. The hub, rim and partitions are preferably formed integrally with the rear disk H¹ of the reaction wheel and engage with the front disk thereof and these parts are rigidly secured together so as to form a steam tight joint between the same by means of transverse screws or bolts h, as shown or otherwise. The hub of the reaction wheel is provided with a circular row of radial openings i each of which is in line with one of the openings f of the shaft F, F¹ and forms therewith an inlet whereby the pressure medium is conducted from the supply port to the inner end of one of the steam chambers. In the periphery of the ring of the reaction wheel are formed a circular row of recesses j corresponding in number to the number of steam chambers. R represents a circular row of tubular nozzles each of which is secured by a screw joint in a radial socket r formed on the rim J and

leading from one of the steam chambers to the corresponding recess *j*. The inner end of each nozzle is provided with a shoulder or collar *r*¹ bearing against the inner side of the rim while its outer end is arranged within the adjacent recess and provided with an outlet opening *s* from which the steam issues tangentially relatively to the axis of rotation of the reaction wheel.

10 *T* represents an impulse wheel arranged in the casing in rear of the reaction wheel and having a hollow hub *t* which receives the adjacent solid portion of the shaft *F*, *F*¹ and is journaled in a bearing in the rear disk or wall 15 of the casing. This impulse wheel is provided with an inner circular row of blades, buckets or wings *t*¹ which project forwardly from said impulse wheel and are arranged around the rim of the reaction wheel so that 20 they will be acted upon or engaged by the steam issuing from the nozzles. Each of these inner blades is preferably curved and arranged so that the impact of the steam is delivered against the concave side of the 25 same.

Around the inner row of blades is arranged a circular row of intermediate blades *U* which project rearwardly from the front disk of the reaction wheel, said disk for this purpose being made somewhat larger in diameter than 30 the companion rear disk of this wheel. Each of the intermediate blades is curved in a direction opposite to that of the inner blades.

V represents a circular row of outer blades 35 arranged around the intermediate blades and projecting forwardly from the peripheral portion of the impulse wheel. Each of these outer blades is curved in a direction opposite to that of the intermediate blades but in the 40 same direction as the inner blades.

W represents a circular row of stationary 45 guide or abutment blades arranged around the outer blades and preferably formed on the ring *B* of the casing. Each of the stationary blades is preferably constructed in the form of a ratchet tooth the front side of which faces the concave side of the outer blades while the inclined rear side thereof faces the convex side of the outer blades.

50 Diametrically opposite the supply port the casing is provided with an exhaust or outlet *w* for the spent steam. As shown in the drawings the supply port is on the underside of the arbor and the exhaust is at the top of the ring *B* of the casing but if desired the relation of the supply port and exhaust may be varied.

As the steam supplied through the conduit *d* issues from the port *e* thereof it passes 60 through the particular inlet *f*, *i* registering therewith and into the corresponding steam chamber, thence through the nozzle of this chamber and then issues tangentially from the outlet thereof. The reaction of the 65 steam upon thus issuing from the outlet of

the steam chamber causes the reaction wheel to turn in the direction of the arrow so that the inlet of the next steam chamber is brought into register with the supply port causing steam in like manner to pass through the same and issue tangentially from the outlet thereof. This action is repeated as the inlets of the several steam chambers are brought successively into register with the supply port.

70 As the steam issues from the outlets of the several steam chambers of the reaction wheel the same impinges against the inner row of blades of the impulse wheel and causes the latter to be turned in a direction opposite to that of the reaction wheel owing to the impact or impelling force of the steam against the inner blades. The curvature of the inner blades causes the steam upon striking the same to be deflected and rebound outwardly at an angle so as to strike the concave sides of the intermediate blades. The steam is now again deflected outwardly at a reverse angle by the intermediate blades and by its reaction against the latter assists the 85 initial steam jets issuing from the nozzles to turn the reaction wheel as before described.

Upon leaving the intermediate blades the steam strikes the concave sides of the outer blades and thereby aids in turning the impulse wheel in a direction opposite the action wheel. As the steam strikes the outer blades the same is deflected outwardly and in a reverse direction so that it impinges 90 against the abrupt faces of the stationary 95 blades or guides from which it reacts and assists the impulse wheel in its rotary movement. As each outer blade arrives opposite the exhaust the pressure medium has spent itself and escapes through the same.

100 Within the bore of the ring *B* and in front of the exhaust a relief chamber *W*¹ is formed which permits free vent of the spent steam from the outer rotatable blades to the exhaust, while on the rear side of the exhaust the casing ring extends close to the outer edge of the outer blades so as to form a baffle *w*¹ which prevents the steam from backing up and escaping directly to the exhaust 110 before it has expended its force.

115 While the steam chambers are in communication with the supply conduit the steam issuing from the outlet thereof acts directly and at high pressure against the blades but when the steam chambers during the forward movement of the impulse wheel are cut off from the live steam supply then the steam in the chamber operates by expansion and at low pressure against the blades. The supply port shown in the drawings is of such 120 width that it is capable of communicating at one time with one steam chamber and at another time with two of said chambers so that live steam is being supplied at all times to either one or two of the chambers which 125 130

operates directly against the blades while the steam is operating expansively on the blades in the remaining four chambers which for the time being are cut off from the steam supply. The full propelling effect of the steam is thus obtained before the same finally reaches the exhaust.

If desired, the motion of the impulse and reaction wheels may be transmitted by separate means to the place of consumption but if desired the motion of these two wheels may be united, the preferred means for this purpose shown in the drawings being constructed as follows:

15 X represents a driven shaft and Y a counter shaft which are journaled in bearings on the rear wall of the casing and a hood or bracket z secured to this wall.

x represents a gear wheel secured to the hub of the impulse wheel and meshing with a gear wheel x' on the counter shaft.

z¹ represents a master gear wheel secured to the driven shaft and meshing with a pinion z² on the shaft of the reaction wheel and 25 a pinion z³ on the counter shaft. By this means the rotary movements of the impulse and reaction wheels are converted or translated and caused to move in the same direction, thereby uniting the power in the driven 30 shaft from which latter the motion may be transmitted to the place of consumption by any suitable means.

The engine shown in Figs. 1-7 of the drawings is designed to utilize both the reaction and impulse effect of the steam whereby the maximum power is derived from the same. For the purpose of simplifying the engine the same may be constructed so as to utilize only the reaction of the steam. Such 40 a simplified engine is shown in Figs. 8 and 9. In this construction no impulse wheel is employed but in its stead two circular rows of blades U¹, V¹ are mounted on the rear wall A² of the casing on the inner and outer sides 45 of the intermediate blades so that they operate as guides against which the steam impinges upon leaving the outlets of the steam chamber and the faces of the rotatable intermediate blades.

50 When the engine is designed to employ two motor wheels which rotate in opposite directions the engine runs practically without any vibration.

If desired, the number of rows of concentric blades or buckets with which the steam 55 engages successively before reaching the exhaust may be less than that shown in the drawings when an engine of less power is required and greater than the number shown 60 in the drawings when more power is desired.

By proportioning the number of concentric rows of blades in accordance with the available steam supply or pressure the full benefit of the steam is obtainable before it 65 escapes to the exhaust.

While a single supply port e answers the purpose in smaller sizes of engines a plurality of such ports may be employed in larger sizes of engines in order to furnish ample live steam to some of the steam chambers 70 while the steam is operating expansively in the other chambers. The number of exhausts w may also be multiplied in larger sizes of engines.

I claim as my invention:

75 1. A turbine engine comprising a pressure medium supply conduit having a supply port, a rotatable member having a plurality of chambers each of which is provided with an inlet adapted to register with said port of the supply conduit and an outlet, and a plurality of blades or buckets arranged to be acted on by the pressure medium issuing from the outlets of said chambers.

80 2. A turbine engine comprising a pressure medium supply conduit having a supply port, a rotatable member having a plurality of chambers each of which is provided with an inlet adapted to register with said port of the supply conduit and a tangential outlet, 85 and a plurality of blades or buckets arranged to be acted on by the pressure medium issuing from the outlets of said chambers.

90 3. A turbine engine comprising a pressure medium supply conduit having a supply port, a rotatable member having a plurality of chambers each of which is provided with an inlet adapted to register with said port of the supply conduit and an outlet, and a circular row of blades arranged to be acted on by the pressure medium issuing from said outlets and another circular row of blades 95 arranged to be acted on by the pressure medium after the same leaves the first mentioned row of blades.

100 4. A turbine engine comprising a pressure medium supply conduit having a supply port, a rotatable member having a plurality of chambers each of which is provided with an inlet adapted to register with said port of the supply conduit and an outlet, an inner circular row of blades arranged to be acted on by the pressure medium issuing from said outlets, 105 an intermediate circular row of blades arranged to be acted on by the pressure medium after the same leaves the inner blades, and an outer circular row of blades arranged to be acted on by the pressure medium after the same leaves the intermediate 110 blades.

115 5. A turbine engine comprising a pressure medium supply conduit having a supply port, a rotatable member having a plurality of chambers each of which is provided with an inlet adapted to register with said port of the supply conduit and an outlet, a circular row of blades arranged to be acted on by the pressure medium issuing from said outlets, 120 an inclosing casing having an exhaust, and a circular row of stationary blades arranged

125 120 130

within the casing adapted to be acted on by the pressure medium before the same escapes through said exhaust.

6. A turbine engine comprising a pressure medium supply conduit having a supply port, a rotatable member having a plurality of chambers each of which is provided with an inlet adapted to register with said port of the supply conduit and an outlet, a circular row of rotatable blades arranged to be acted on by the pressure medium issuing from said outlets, and a circular row of blades rotatable with said member and arranged to be acted on by the pressure medium after the same leaves the first mentioned row of blades.

7. A turbine engine comprising a pressure medium supply conduit having a supply port, a rotatable member having a plurality of chambers each of which is provided with an inlet adapted to register with said port of the supply conduit and an outlet, an inner circular row of blades arranged to be acted on by the pressure medium issuing from said outlets, a circular row of rotatable intermediate blades arranged to be acted on by the pressure medium after the same leaves the inner blades, and a circular row of outer rotatable blades arranged to be acted on by the pressure medium after the same leaves the intermediate blades.

8. A turbine engine comprising a pressure medium supply conduit having a supply port, a rotatable member having a plurality of chambers each of which is provided with an inlet adapted to register with said port of the supply conduit and an outlet, an inner circular row of blades arranged to be acted on by the pressure medium issuing from said outlets, a circular row of rotatable intermediate blades arranged to be acted on by the pressure medium after the same leaves the inner blades, and a circular row of outer blades rotatable with said inner blades and arranged to be acted on by the pressure medium as the same leaves the intermediate blades.

9. A turbine engine comprising a pressure medium supply conduit having a supply port, a rotatable member having a plurality of chambers each of which is provided with an inlet adapted to register with said port of the supply conduit and an outlet, an inner circular row of blades arranged to be acted on by the pressure medium issuing from said outlets, a circular row of rotatable intermediate blades arranged to be acted on by the pressure medium after the same leaves the inner blades, a circular row of outer blades rotatable with said inner blades and arranged to be acted on by the pressure medium as the same leaves the intermediate blades and gearing operatively connecting said blades and constructed to transmit the movement thereof in the same direction.

10. A turbine engine comprising a pres-

sure medium supply conduit having a supply port, a rotatable member having a plurality of chambers each of which is provided with an inlet adapted to register with said port of the supply conduit and an outlet, an inner circular row of blades arranged to be acted on by the pressure medium issuing from said outlets, a circular row of rotatable intermediate blades arranged to be acted on by the pressure medium after the same leaves the inner blades, a circular row of outer blades rotatable with said inner blades and arranged to be acted on by the pressure medium as the same leaves the intermediate blades, a circular row of stationary blades arranged to be acted on by the pressure medium after the same leaves the outer blades, and a casing inclosing said blades and having an exhaust.

11. A turbine engine comprising an arbor having a supply conduit for a pressure medium and a laterally opening supply port, a wheel rotatable about said arbor and having an annular row of chambers, individual inlets for said chambers arranged in the hub of said wheel and adapted to register successively with said port and individual outlets at the periphery of said wheel, and blades arranged to be engaged by the pressure medium issuing from said outlets.

12. A turbine engine comprising an arbor having a supply conduit for a pressure medium and a laterally opening supply port, a wheel rotatable about said arbor and having an annular row of chambers, individual inlets for said chambers arranged in the hub of said wheel and adapted to register successively with said port, a plurality of recesses in its periphery, and a socket extending from each chamber to one of said recesses, a nozzle arranged in each socket and having a tangential outlet opening at its outer end within the respective recess, and a circular row of blades arranged to be engaged by the pressure medium issuing from said outlet openings.

13. A turbine engine comprising an arbor having a supply conduit for a pressure medium and a laterally opening supply port, a wheel rotatable about said arbor and composed of two separated disks, a hub connecting said disks and provided with a plurality of inlet openings which are adapted to register successively with the supply port, an annular rim connecting said disks and provided with a plurality of outlets and a plurality of radial ribs connecting said disks, hub and rim and forming with the same a plurality of chambers each of which is provided with one of said inlets and one of said outlets, and said ribs, rim and hub being formed on one of said disks and engaging with the other disk, and a circular row of blades arranged to be engaged by the pressure medium issuing from said outlets.

14. A turbine engine comprising an arbor having a supply conduit and a supply port, a shaft having a hollow portion which turns on said arbor, a wheel secured to said shaft and provided with a circular row of chambers, the hub of said wheel and the hollow portion of said shaft being provided with coinciding pairs of openings forming inlets for said chambers, respectively, which are adapted to register successively with said supply port, an outlet nozzle for each chamber arranged at the periphery of said wheel, and a circular row of blades arranged to be engaged by the pressure medium issuing from the nozzles.
15. 15. A turbine engine comprising a pressure medium supply conduit having a port, a reaction wheel having a circular row of chambers, inlets at the inner ends of said chambers adapted to register successively with said supply port and outlets at the outer ends of said chambers, and an impulse wheel provided with a circular row of blades arranged to receive the impact of the pressure medium issuing from said outlets.
- 20 16. A turbine engine comprising a pressure medium supply conduit having a port, a reaction wheel having a circular row of chambers, inlets at the inner ends of said chambers adapted to register successively with said supply port, and outlets at the outer ends of said chambers, an impulse wheel provided with a circular row of blades arranged to receive the impact of the pressure medium issuing from said outlets.
- 25 17. A turbine engine comprising a pressure medium supply conduit having a port, a reaction wheel having a circular row of chambers, inlets at the inner ends of said chambers adapted to register successively with said supply port, and outlets at the outer ends of said chambers, an impulse wheel provided with a circular row of blades around said outlets, and a circular row of blades mounted on the reaction wheel and arranged around said blades of the reaction wheel.
- 30 18. A turbine engine comprising a pressure medium supply conduit having a port, a reaction wheel having a circular row of chambers, inlets at the inner ends of said chambers adapted to register successively with said supply port and outlets at the outer ends of said chambers, an impulse wheel, an inner circular row of blades arranged on the impulse wheel around said outlets, an intermediate circular row of blades arranged on the reaction wheel around the inner blades, and an outer circular row of blades arranged on the impulse wheel around the intermediate blades.
- 35 19. A turbine engine comprising a pressure medium supply conduit having a port, a reaction wheel having a circular row of chambers, inlets at the inner ends of said chambers adapted to register successively with said supply port and outlets at the outer ends of said chambers, an impulse wheel, an inner circular row of blades arranged on the impulse wheel around said outlets, an intermediate circular row of blades arranged on the reaction wheel around the inner blades, an outer circular row of blades arranged on the impulse wheel around the intermediate blades, a circular row of stationary blades arranged around said outer blades, and a casing inclosing said wheels and blades and having an exhaust.

Witness my hand this 23rd day of December, 1907.
